UNITED STATES PATENT OFFICE.

WILLIAM H. DEY, OF NEWARK, NEW JERSEY, ASSIGNOR TO UNITED STATES RADIUM CORPORATION, A CORPORATION OF DELAWARE.

PLATE FRAME.

Application filed March 10, 1922. Serial No. 542,580.

To all whom it may concern:

Be it known that I, WILLIAM H. DEY, a citizen of the United States, residing at Newark, in the county of Essex, State of New Jersey, have invented certain new and useful Improvements in Plate Frames; and I do hereby declare the following to be a full, clear, and exact description of the invention, such as will enable others skilled in the art to which it appertains to make and use the same.

This invention relates to display devices and has reference particularly to such devices as are employed in connection with the display of house numbers. More specifically the invention pertains to frames for displaying numbers which are mounted on plates that have relatively high intrinsic value and are therefore liable to theft; an example of such a plate is one for use in displaying a house number consisting of a plate of glass with the number painted thereon in radium luminous paint.

One object of the invention is to provide a frame for holding such number plates which is of simple construction and therefore inexpensive to manufacture, which may be easily attached to the wall of a house or a door post and which is so constructed as to minimize the liability of theft.

In accordance with the present invention, these objects are attained by the production of a frame for receiving and holding number plates formed from sheet metal and so constructed as to hold one or more plates and form a border around each plate. The frame is so constructed as to permit of inserting the number plates edgewise at one of the lateral edges of the frame, the plate or several plates as the case may be, being moved edgewise into the frame until they reach their final positions. The frame is so constructed that the plates may be inserted into it only at one of the lateral edges and at this edge there is an integral flange on the frame which snaps over the edge of the plate or plates so as to prevent withdrawal.

The frame is adapted to be secured upon its support by securing means such as screws which coat with members that are integral with the frame and which lie at the back of the frame. The object of this arrangement of the parts is to have the se-

curing means so located that they are readily accessible while mounting the frame in position but are covered and wholly concealed by the plate which is mounted within the frame. Thus, the securing means is made accessible only by the removal of the plate and removal of the plate is prevented by the flange at the edge of the frame which coats with the edge of the plate.

The preferred embodiment of the invention is illustrated in the accompanying drawings, in which Fig. 1 is a perspective view of a frame with two number plates therein; Fig. 2 is a cross-sectional view on line 2-2 of Fig. 1; Fig. 3 is a back view of the frame; Fig. 4 is a sectional view showing the frame attached to a support and Fig. 5 is an end view.

The drawings show a frame designed to hold two number plates arranged edge to edge, but, of course, the same construction may be employed in providing a frame for any number of plates. The frame is of rectangular form and it is made from a piece of sheet metal which is cut out to form one or more openings and a rectangular border around each of the openings. The metal of the frame is bent backwardly from each of the several frame members to form the edge members of the frame and at all of the edges except one of the lateral edges these rearwardly bent portions extend back to the plane of the back of the frame. At one edge the flange extends only part way back so as to permit of the introduction of the number plates under the flange thus provided.

Referring to the drawings, the frame itself is shown at 6 as being of rectangular form and adapted to receive two number plates 7. The metal from which the frame is formed is bent backwardly as indicated at 8 to form flanges extending back to the plane of the rear surface of the frame, except that at one of the lateral edges, the flange 9 is a narrow one extending back only a short distance as is indicated in Fig. 5. The flanges at the top and bottom edges of the frame are extended by flanges 10 which are bent toward each other in the general plane of the frame and each of these flanges 10 is provided with openings 11 to receive securing screws, the openings being countersunk so that the screw heads will lie within the openings in the flanges.

With the frame so constructed securing it upon its support is readily effected by inserting screws 12 through the openings 11 and screwing them into the support until 5 their heads lie wholly within the openings 11. Then one of the number plates 7 is introduced into the frame at the edge of the flange 9 and moved along edgewise. In a frame for holding two or more members 10 this first number plate is moved along under the intermediate bars 13 of the frame until its movement is arrested by the flange 8 at the opposite edge of the frame. Another or other number plates are then introduced 15 and moved along and as the last one is moved in a position within the frame, the flange 9 at the lateral edge of the frame snaps over the edge of the plate and holds it against withdrawal. Thus, all of the 20 securing screws 12 lie under the plates and are inaccessible for removal otherwise than by first removing the plates, but the plates cannot be withdrawn as the end one of the plates is held by the flange 9 and obstructs 25 movement of all of the other plates. The end plate may readily be inserted under the flange 9 because of the elasticity of the metal and when it reaches its final position this elasticity causes the flange 9 to spring over 30 the edge of the plate. But withdrawal of the plate is difficult as force to move the plate laterally can only be applied to it by pressing upon its surface and the flange 9 serves to prevent any movement of the plate 35 due to force applied in this manner.

The glass plates 7 are provided with numerals or other characters to be displayed, these characters being secured to or mounted in the back face of the plates in any con-

venient manner. The back face of the plates 40 is then covered with a protective sheet or cloth 14, or other like material.

I claim:

1. A frame having a pair of apertures 45 therein defined by side and end walls and by an intermediate bar, the side walls of the frame being rearwardly and inwardly bent to form a slot and the inward extensions affording means to attach the frame to a support, said attaching means being so positioned as to be operable through the apertures when the slot is empty, and a pair of plates insertible in the slot and having their 50 abutting edges concealed by the intermediate bar, such plates serving to conceal the attaching means.

2. A frame having a pair of apertures 55 therein defined by side and end walls and by an intermediate bar, the side walls of the frame being rearwardly and inwardly bent to form a slot, a pair of plates insertible in the slot and having their abutting edges concealed by the intermediate bar, and flanges extending from each end wall and bearing against the ends of the plates to 60 hold said plates with their abutting edges concealed.

3. A frame having a pair of apertures 65 therein defined by side and end walls and by an intermediate bar, flanges extending from said frame to form a slot, a pair of plates insertible in the slot and having their abutting edges concealed by the intermediate bar, and flanges extending from said frame 70 to bear against the ends of said plates to hold them in said slot.

In testimony whereof I affix my signature.
WILLIAM H. DEY.
